UNITED STATES PATENT OFFICE.

ERNEST JACQUES ROUX, OF GENEVA, SWITZERLAND, ASSIGNOR TO THE ANCIENNE FABRIQUE VACHERON AND CONSTANTIN, (LIMITED,) OF SAME PLACE.

HAND-SETTING MECHANISM FOR WATCHES.

SPECIFICATION forming part of Letters Patent No. 406,307, dated July 2, 1889.

Application filed February 14, 1889. Serial No. 299,882. (No model.)

To all whom it may concern:

Be it known that I, ERNEST JACQUES ROUX, manufacturer, of Geneva, Switzerland, have invented an Improvement in Hand-Setting Mechanism for Watches, of which the following is a specification.

This invention is adapted to that class of hand-setting device in which the crown upon the shank can be moved endwise as well as rotated. When such crown is pressed toward the watch, it remains in the normal position, and is adapted to the winding of the watch; but when the crown is drawn outwardly the hand-setting mechanism is brought into action and the crown can be rotated in either direction, as may be necessary.

In the drawings, Figure 1 is an elevation of the mechanism connected with the crown and in the normal position for winding. Fig. 2 is a vertical section of the parts in the position of Fig. 1. Fig. 3 is an elevation of the parts with the crown connected to the hand-setting mechanism. Fig. 4 is a vertical section of the parts shown in Fig. 3, and Fig. 5 is a detached view of the push-pin.

I have represented a portion of the watch-plate at C and a portion of the stem at A. Upon the plate C there is a bridge D, and at one side thereof the wheel K is connected by a pivot-screw S, and this wheel K is connected to the hand-setting wheels, which wheels are of any ordinary character. The pin B passes through this bridge D and also through the tubular axis E, and the upper part of the tubular axis is polygonal for receiving the square end A of the winding-stem. This winding-stem A is of any ordinary character, and it passes through the shank of the watch and is connected to the crown. When the crown is in its normal position, the stem A rests against the end of the pin B and such pin B occupies the position shown in Figs. 1 and 2, and when the stem A is drawn up the pressure of the pin B is released and such pin is moved with the parts, hereinafter described, and assumes the position shown in Figs. 3 and 4.

The tubular axis E has around it the pinion F, which is loose thereon, and it is geared

to the spring-barrel by any suitable wheels, 50 and around the tubular axis E there is a sliding clutch G, there being a feather or square upon the tubular axis E, by which the sliding clutch G may be rotated at all times, and this clutch G is grooved peripherally for the end 55 g of the lever H, by which end motion is given to such clutch, and at the end of the clutch G and on the crown-pinion F there are ratchet-teeth which engage each other in the direction in which the mainspring is wound up; 60 but such teeth slide over each other when the stem is moved in the opposite direction, the teeth separating and the end movement of the clutch G being allowed for by the spring J, that acts upon the lever H, and at the end 65 of the clutch G next the setting-gear K are teeth that match such gear K when the clutch is moved into contact therewith, and there is a lever I, having one end i" adjacent to the end of the pin B and the other end i' adjacent 70 to the toe h upon the lever H.

The spring J is forked and connected by a screw to the watch-plate, and it is free to swing upon this screw, if necessary. One end of the spring J bears against the lever H 75 and the other end against the lever I. When the pin B is pushed into the position shown in Fig. 1, the lever I is moved thereby, and the end i', acting against the toe h, moves the lever H and slides the clutch G into its normal position, and the spring J is compressed. When the stem A is drawn up, the expansion 80 of the spring J moves both levers H and I, swinging the end i' away from the toe h and swinging the lever H, so that the end g moves 85 the clutch G endwise and causes it to engage with the hand-setting wheel K, and the parts assume the position shown in Fig. 3, and one end of the spring J rests upon the screw M, so as to prevent the spring moving the lever 90 I any farther than the position shown in Fig. 3, and when the hand-setting has been accomplished the pin B is moved endwise by pressure on the stem A, and the lever I acts against the toe h of the lever H and restores the parts 95 to their normal position, with the toe h resting upon the end i' of the lever I, as shown in Fig. 1. The pin k upon the lever I allows

for moving this lever I by a pair of pliers, or otherwise, when the parts are disconnected from the watch-stem.

The screw M may have a conical head to 5 adjust the point at which it arrests the movement of the spring J and lever I.

I claim as my invention—

The combination, with the stem A and tubular axis E, of the clutch G, sliding upon the 10 tubular axis, the lever H, for moving the slid-

ing clutch, the lever I, pin B, and the spring J, for acting upon the respective levers, substantially as set forth.

In testimony whereof I have signed my name to this specification in the presence of two sub- 15 scribing witnesses.

ERNEST JACQUES ROUX. [L. S.]
